CLAIM

The ornamental design for an electromagnetic valve, as shown and described.

DESCRIPTION

FIG. 1 is a front elevational view of an electromagnetic valve embodying our new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is an enlarged sectional view thereof taken along line 7—7 in FIG. 1;

FIG. 8 is a top, front and left side perspective view of FIGS. 1—6; and,

FIG. 9 is a bottom, rear and right side perspective view thereof.

The broken lines showing interior portions of the valve are for illustrative purposes only and form no part of the claimed design.
